UNITED STATES PATENT OFFICE.

CHARLES O. ORMSBEE, OF DETROIT, MICHIGAN, ASSIGNOR TO LEONARD A. YOUNG, OF HIGHLAND PARK, MICHIGAN.

SEAT-SPRING.

1,199,411.

Specification of Letters Patent. Patented Sept. 26, 1916.

Application filed March 8, 1916. Serial No. 82,859.

To all whom it may concern:

Be it known that I, CHARLES O. ORMSBEE, a citizen of the United States, residing at Detroit, county of Wayne, State of Michigan, have invented a certain new and useful Improvement in Seat-Springs, and declare the following to be a full, clear, and exact description of the same, such as will enable others skilled in the art to which it pertains to make and use the same, reference being had to the accompanying drawings, which form a part of this specification.

This invention relates to springs and upholstering, and comprises a border strip of the channel type arranged to both hold the spiral springs and the lower edge of the upholstering.

In the drawings—Figure 1 is a side elevation of a fragment of an automobile seat cushion. Fig. 2 is a fragmentary view looking down on the top of the border strip; that portion of the view at the left showing the border strip stamped over the upholstering skirt, while that portion of the view at the right shows the strip ready to receive the upholstering skirt. Fig. 3 is a vertical cross section on the line A—A of Fig. 1. Fig. 4 is a vertical cross section on the line B—B of Fig. 1, but omitting the doubled-in lower flange of the channel strip, this being an alternative construction.

a designates the upholstering facing or skirt; *b* the spiral springs, and *c* the border strip. The border strip is a channel strip which may or may not have the lower flange *d* doubled back upon itself. Fig. 3 shows the lower flange doubled in and Fig. 4 shows this doubled-in portion omitted. This channel strip is provided with struck-out lips *e* which are turned inwardly over the lower coils of the spiral springs *b* by the spring manufacturer when the seat spring is made. This is clearly indicated on the right side of Fig. 2. The remaining major portion of the upper flange of this strip is left in the position shown at the right of Fig. 2. In this position the strip forms an upwardly opening groove to receive the lower edge of the upholstering facing *a*,

which is ordinarily provided with a cord *f*. 50 The trimmer may place this lower edge of the upholstering facing in this upwardly opening groove and then pinch the upper flange down over the upholstering facing and cord *f* in the manner shown in Fig. 4 55 and at the left in Fig. 2.

I am aware that it is old to use a border strip which both holds the spiral springs and secures the lower edge of the upholstering facing, but the customary strip of this 60 character heretofore has been one of **S** shape in cross section, providing two distinct grooves, one for pinching the lower coils of the spiral springs and the other for pinching the lower edge of the upholstering 65 facing. With my new strip as above described, I can employ a single groove channel strip both to secure the upholstering facing and the spiral springs, thereby effecting considerable saving in material. 70

What I claim is:

1. In a seat cushion, a border strip in the form of a channel strip having an inwardly opening groove and having portions of the upper flange struck in and turned 75 over to form clips to secure the lower coils of the spiral springs and the remaining portions of the upper flange being arranged to be turned in to secure the upholstering facing edge. 80

2. In a seat cushion, a border strip comprising a channel strip having an inwardly opening groove and its lower flange doubled back upon itself, portions of the upper flange being struck out to be turned down over the 85 lower coils of the spiral springs to form clips for securing the same to the border strip and the remaining major portion of the upper flange of the strip forming an upwardly and inwardly facing groove to receive the lower edge of the upholstering facing which may be secured to the border strip by pinching such remaining major portions of the upper flange thereover. 90

In testimony whereof, I sign this specification. 95

CHARLES O. ORMSBEE.
